[57] CLAIM

The ornamental design for an inflatable dome hat, substantially as shown.

DESCRIPTION

FIG. 1 is a front and top right perspective view of an inflatable dome hat showing my new design, as seen when worn;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a front and top right perspective view similar to FIG. 1 in a deflated condition;

FIG. 9 is a left side elevational view thereof;

FIG. 10 is a right side elevational view thereof;

FIG. 11 is a front elevational view thereof;

FIG. 12 is a rear elevational view thereof;

FIG. 13 is a top plan view thereof; and

FIG. 14 is a bottom plan view thereof.
